COOLING SYSTEM FOR INTERNAL-
COMBUSTION ENGINES

Elmer C. Kiekhaefer, Cedarburg, Wis.

Application October 26, 1949, Serial No. 123,566

9 Claims. (Cl. 123—41.29)

1

This invention relates to internal-combustion engines and particularly to water cooling systems therefor.

The invention provides a plurality of coolant chambers which are disposed to receive coolant under pressure from a pump operated by the engine to cool specific portions of the engine. The chambers are connected in series and provided with discharge openings whereby certain of the chambers individually receive coolant for circulation according to the pressure of the coolant supply and the speed and cooling requirements of the engine.

An object of the invention is to regulate the cooling of different parts of the engine according to the operating requirements of the engine.

Another object is to eliminate thermostatic devices ordinarily required to regulate the engine cooling.

Another object is to cool specific portions of the engine at predetermined relative temperatures.

A more particular object is to provide maximum cooling of parts of a two-cycle engine adjacent the exhaust ports and controlled cooling of other parts of the engine.

These and other objects and advantages will be more fully set forth in the following description of a preferred embodiment of the invention as illustrated in the accompanying drawings.

In the drawings:

Figure 1 is a side elevation of a two-cycle engine for an outboard motor having a vertically disposed crankshaft and with parts thereof broken away and sectioned to show two of the coolant chambers of the engine;

Fig. 2 is an enlarged transverse section taken on line 2—2 of Figure 1;

Fig. 3 is a side elevation of the opposite side of the engine with parts broken away to show the third coolant cavity;

Fig. 4 is a vertical transverse section through the engine adapted to show the several coolant chambers and passages;

Fig. 5 is a diagrammatic illustration of the cooling circulation at low speeds; and

Fig. 6 is a diagrammatic illustration of the cooling at high speed.

The two-cycle engine 1 shown in the drawings is mounted on the drive shaft housing 2 of an outboard motor, not shown in full. The water pump 3, shown diagrammatically in Fig. 4 only, is driven through the drive shaft 4 by engine 1 and normally receives water from the body of water in which the motor is being operated. The

pipe 5 connects pump 3 and the engine to deliver the water thereto for cooling of the engine.

Pump 3 may be of any type and either of centrifugal or displacement operation with a delivery which usually varies substantially with the speed of operation of engine 1.

The crankshaft 6 of engine 1 is vertically disposed and the cylinder sleeves 7 are arranged in line with their axes in a common vertical plane 10 which includes the axis of the crankshaft.

The piston 8 in each cylinder 7 is connected to crank shaft 6 by the connecting rod 9 and at the lower end of each stroke uncovers the intake ports 10 and exhaust ports 11 in respective opposite sides of the cylinders.

The crankcase of engine 1 comprises the member 12 and complementary skirt portions 13 of the cylinder block 14 which define individual crank chambers 15 for each piston 8 and cylinder 7.

In the operation of engine 1 the air-fuel mixture is supplied by the carburetors 16 to the several crank chambers 15 through valve means, not shown, and is transferred from the crank chambers through the individual passages 17 and the ports 10 into the respective cylinders 7 when piston 8 uncovers ports 10 with each revolution of crankshaft 6. The exhaust of each cylinder 7 passes through ports 11 into the chambers 18.

Cylinder block 14 is comprised of a lightweight alloy which is cast around sleeves 7 and closes the upper ends thereof to form the cylinder domes 19. The several recesses formed in block 14 extend from the crank chambers 15 alongside cylinder sleeves 7 to ports 10 and comprise the transfer passages 17 referred to above.

The plate 20 secured to the side of block 14 closes recesses which are formed in one side of the block and which overlies cylinders 7. The recesses with plate 20 define the exhaust chambers 18 referred to above. Chambers 18 open downwardly of block 14 directly into drive shaft housing 2 for delivery and underwater discharge of the exhaust from the lower end, not shown, of housing 2.

The coolant chamber 21 formed in block 14 surrounds the upper ends of sleeves 7 and domes 19 and is closed by the cover member 22 bolted to the end of block 14. Chamber 21 is connected to pump 3 by pipe 5 which is received in the lower end of block 14 and opens directly into the lower end of chamber 21 to deliver the water thereto.

The jacket 23 is secured to block 14 over plate 20 and is provided with a recessed inner

face which with plate 20 provides the coolant chamber 24. The openings 25 in the upper end of plate 20 register with the horizontal passage 26 formed in block 14 to open into the upper end of chamber 21. Openings 25 and passage 26 provide communication between chambers 21 and 24 at their upper levels, and for delivery of the water from chamber 21 to chamber 24.

The discharge opening 27 in plate 20 from the lower end of chamber 24 registers with the passage 28 in block 14. Passage 28 extends transversely of the block and opens downwardly directly into housing 2 to provide for the gravity discharge of a certain amount of water from chamber 24, as will be more fully described.

The plate 29 secured to the side of block 14 oppositely of plate 20 closes a recess formed in that side of the block which extends the height of the block and overlies cylinders 7 and passages 17. The recess with plate 29 defines the coolant chamber 30.

The passage 31 extends across the top of block 14 from the upper end of chamber 30 and registers with the hole 32 in plate 20 which opens into chamber 24 on the opposite side of the block. Hole 32 and passage 31 thus provide communication between chambers 24 and 30 at their upper levels and for delivery of water coolant from chamber 24 to chamber 30.

The discharge opening 33 at the bottom of block 14 opens from chamber 30 directly into housing 2 and provides for the gravity discharge of water from chamber 30.

Chamber 24 is disposed immediate to exhaust chambers 18 and serves to cool plate 14 and adjacent parts of engine 1. The cooling of the exhaust gases passing through chambers 18 is also effected.

In the operation of engine 1 the heat transfer and protection of other parts of the engine against overheating afforded by the coolant circulating through chamber 24 is essential to continuous, high speed operation. At low speeds and particularly in cold weather such cooling is of less importance and may be dispensed with entirely.

Chamber 30 on the opposite side of engine 1 is disposed immediate to crank chambers 15, the intake side of cylinders 7, and extends over passages 17. The water coolant circulating through chamber 30 serves to prevent overheating of the parts on that side of engine 1 and particularly to prevent heating of the fuel charge entering the cylinders from the crank chambers through passages 17.

In continuous high speed operation of the engine without adequate cooling, heating of the fuel charge generally lowers the thermal efficiency of the engine and may cause excessive amounts of liquid fuel in the crank chambers 15 and passages 17 to vaporize and interfere with the operation of the engine.

However, in operating the engine continuously at low speeds such cooling is unnecessary and undesirable since the parts of the engine referred to may be excessively cooled so that the fuel vapor is condensed in the crank chambers and transfer passages.

According to the invention, chambers 21, 24 and 30 are arranged in series so that the water is first circulated over the cylinder domes 19 which require the greatest amount of cooling. Thereafter, the water is further heated while circulating through chamber 24 as described. The heated water which is not discharged through opening 21 from chamber 24 is then circulated into passage 31 and through chamber 30.

It should be understood that while in practice the actual temperature gradients of the water is not very great, the invention provides for maximum cooling of the cylinders and prevents excessive cooling of the transfer passages.

According further to the invention the sizes of discharge openings 27 and 33 relative to the delivery of pump 3, may be predetermined so that at low speeds, as shown in Fig. 5, the water coolant delivered by pump 3 fills chamber 21, passes into and through chamber 24 and is discharged through opening 27. Opening 27 should be of such size so that at low engine speeds and low volumetric delivery of pump 3, no water is circulated through chamber 30 and so that at higher engine speeds when cooling of passages 17 is required chamber 24 fills entirely with water and a portion of the water passes into chamber 30.

The size of opening 33 is determined so that the water which enters chamber 30 at intermediate engine speeds, as shown in Fig. 6, passes directly therethrough and by gravity is discharged through opening 33. At high engine speeds chambers 24 and 30 are completely filled when the delivery of pump 3 is greater than the amount which normally is discharged through openings 27 and 33 from chambers 24 and 30, respectively.

The cooling system is particularly adapted for outboard motors which are operated at different times in cold water and cold weather or in hot weather, and eliminates the need of thermostatic adjustment means. The cooling system provides, when required, positive pressure circulation of water over the transfer passages of the engine.

Various embodiments of the invention may be employed within the scope of the following claims.

I claim:

1. In an engine of the class described, a coolant pump operated by the engine adapted to deliver coolant under pressure at varying rates in relation to the speed of operation of the engine, and a coolant chamber connected to said pump to receive coolant therefrom, said chamber having a lower outlet of a specific size in relation to the delivery of said pump whereby at predetermined higher delivery rates of said pump and greater cooling requirements of the engine the coolant is retained within the capacity of said chamber for cooling purposes and discharged through said outlet under pressure and at lower delivery rates and nominal cooling requirements the coolant passes immediately by gravity through said chamber and from said chamber through said outlet.

2. In an engine of the class described, a substantially positive-displacement pump driven by the engine adapted to deliver coolant under pressure at varying rates in direct relation to the speed of operation of the engine, a first coolant chamber connected to said pump to receive coolant therefrom, and a second coolant chamber communicating at its upper end with the upper end of said first chamber and disposed to receive the coolant therefrom, said chambers having lower outlets of specific sizes in relation to the delivery of said pump whereby at predetermined higher delivery rates and greater cooling requirements of the engine the coolant delivered to said first chamber in excess of the gravity discharge through the lower outlet of said first chamber is circulated through said second chamber.

3. The invention as defined in claim 1 and embodied in a two-cycle engine having a transfer

passage wherein the coolant chamber is disposed adjacent the transfer passage.

4. The invention as defined in claim 2 and embodied in a two-cycle engine having an exhaust chamber and a transfer passage and wherein the first coolant chamber is disposed adjacent the exhaust chamber and the second chamber is disposed adjacent the transfer passage.

5. In a crankcase induction two-cycle engine of the type having a crank chamber, a combustion chamber, an exhaust chamber communicating with said combustion chamber to receive exhaust gases therefrom, and a transfer passage from said crankcase and opening into said combustion chamber to deliver successive fuel charges thereto, several wall members defining first, second and third coolant cavities respectively adjacent said combustion chamber, said exhaust chamber and said transfer passage, and coolant delivery means disposed to circulate coolant through said first, second and third chambers under pressure in that order.

6. In a crankcase induction two-cycle engine of the type having a crank chamber, a combustion chamber, an exhaust chamber communicating with said combustion chamber to receive exhaust gases therefrom, and a transfer passage from said crankcase and opening into said combustion chamber to deliver successive fuel charges thereto, several wall members defining first, second and third coolant cavities respectively adjacent said combustion chamber, said exhaust chamber and said transfer passage, coolant delivery means disposed to circulate coolant through said first, second and third chambers under pressure in that order, gravity outlets for said second and third chambers respectively of specific sizes in relation to the rate of said delivery means, and means for varying the delivery of said means whereby the circulation of water through said third chamber may be entirely dispensed with and the water level within said second chamber may be controlled.

7. In an internal combustion engine, a cylinder block having wall members defining first, second and third chambers adapted to receive a coolant for cooling separate portions of the block, said first and second chambers and said second and third chambers communicating with each other

at their upper levels, variable delivery means disposed to introduce coolant to said first chamber under pressure, and gravity outlets for said second and third chambers respectively of specific sizes in relation to the variable rate of said delivery means whereby the circulation of coolant through said third chamber may be entirely withheld and the water level within said second chamber controlled.

8. In an engine of the class described, a pump delivering coolant under pressure at a rate varying generally directly with the speed of engine operation, a first coolant chamber connected to receive coolant from said pump under pressure for circulation and having a restricted outlet limiting the flow of coolant therethrough, and a second chamber having limited communication with said first chamber and a restricted lower outlet, said second chamber receiving coolant from said first chamber at a rate varying with the delivery of said pump and the effective restriction of the outlet of said first chamber, the lower outlet of said second chamber being of a size allowing free flow of coolant through said second chamber during the lower range of pump delivery and engine operation and effecting filling of and restricted flow of coolant through said second chamber during the higher range of pump delivery and engine operation.

9. The invention as defined in claim 8 and embodied in a two-cycle engine having an exhaust chamber and a transfer passage and wherein the first coolant chamber is disposed adjacent the exhaust chamber and the second chamber is disposed adjacent the transfer passage.
